UNITED STATES PATENT OFFICE.

WILLIAM F. MILLER, OF BOSTON, MASSACHUSETTS.

TRUNK.

SPECIFICATION forming part of Letters Patent No. 532,330, dated January 8, 1895.

Application filed May 28, 1894. Serial No. 512,764. (No model.)

To all whom it may concern:

Be it known that I, WILLIAM F. MILLER, of Boston, in the county of Suffolk and State of Massachusetts, have invented a new and useful Improvement in Trunks, of which the following, taken in connection with the accompanying drawings, is a specification.

My invention relates to a combination device to be applied to trunks for the purpose of furnishing a firm and convenient casing for attaching the hinge pieces, the object being to strengthen the hinge connections and to facilitate the work of attaching the hinges. This object I attain by the mechanism shown in the accompanying drawings, in which—

Figure 1 is a perspective view showing one corner of a trunk with my improvement attached, the trunk being represented as closed.

Fig. 2 is a perspective view showing one corner of a trunk as it appears when open. Fig. 3 is a perspective view showing the interior of the casing with the hinge connections.

In the drawings, A and B represent respectively the cover and the body of a trunk of ordinary construction. The casing for the corner of the cover is represented by the part C C' C² C³ all of a single piece of metal, and D D' D² represents the casing for the corner of the body of the trunk. These casing pieces are to be made substantially as represented in the drawings.

H represents a curved link pivoted to the part C C' C² C³ by the pin H' and to the part D D' D² by the pin H². A second link K is pivoted to the same parts at K' and K². The corner casings and the links H and K are not new nor of my invention, but it is necessary that their construction and use be understood

in order to comprehend my improvements, which I will now describe.

The link K is made with a slot K³ so that it may move in the direction of its length on the pin K². (See Fig. 3.) I have found by trial that a trunk with two links like H and K will not readily open unless one of the links has a slot like K³ to allow of motion on the pivot. I have also found by trial that a cover connected to the body of a trunk by links at each end like H and K will not keep in its proper place in opening; that is, the longitudinal lines of the cover will not remain parallel to the corresponding lines of the body of the trunk. To obviate this defect, I add to the upper casing the members C² and to the lower casings, the members D², and connect them by hinge pieces E. With these additions to the casings I produce a perfect working device.

I claim—

In a trunk hinge device, the combination of the casing pieces made as described, the curved link H pivoted at H' to the cover of the trunk and at H² to the body of the trunk, the link K pivoted to the cover of the trunk and connected by a slot and pin to the body of the trunk; with the hinge C² E D², the members C² and D² being respectively integral with the casing pieces, all substantially as and for the purpose set forth.

In testimony whereof I have signed my name to this specification, in the presence of two subscribing witnesses, on this 11th day of May, A. D. 1894.

WILLIAM F. MILLER.
